UNITED STATES PATENT OFFICE.

GEORGE M. WATSON, OF RAYMOND, ILLINOIS.

ATTACHMENT FOR BARBERS' HAIR-CLIPPERS.

SPECIFICATION forming part of Letters Patent No. 621,439, dated March 21, 1899.

Application filed August 25, 1898. Serial No. 689,537. (No model.)

To all whom it may concern:

Be it known that I, GEORGE M. WATSON, of Raymond, in the county of Montgomery and State of Illinois, have invented certain new and useful Improvements in Attachments for Barbers' Hair-Clippers; and I do hereby declare that the following is a full, clear, and exact description of the invention, which will enable others skilled in the art to which it appertains to make and use the same, reference being had to the accompanying drawings, and to the letters of reference marked thereon, which form part of this specification.

15 My invention relates to hair-clippers, and more particularly to a certain new and useful attachment for barbers' hair-clippers, whereby the hair cut off by the clippers is caught and prevented from falling upon the 20 person or clothing of either the barber or the customer or upon the floor, whereby great annoyance to the customer is prevented and the necessity of cleaning shop immediately after hair-cutting avoided.

25 With this object in view my invention consists in an attachment for barbers' hair-clippers, as will be fully described hereinafter and afterward specifically pointed out in the claims.

30 In the accompanying drawings, Figure 1 is a view in perspective of a pair of clippers grasped in the hand of the operator and equipped with an attachment constructed in accordance with my invention. Fig. 2 is a 35 vertical longitudinal sectional view of the attachment removed from the clippers.

Like letters of reference mark the same parts in both figures of the drawings. Referring to the drawings by letters, A indicates a pair of clippers of any usual or approved type, provided with a screw-stem B and a tap-nut C, by means of which the usual cover or guard for the operating mechanism is secured in position.

45 D indicates my improved attachment, which is a pan or receptacle to catch the clipped

hair. It may be made of any suitable material—such as celluloid, hard rubber, sheet metal, &c.—and of any suitable form, provided only that the end E is formed to properly fit upon the face of the clipper and has an opening to pass over the screw-stem B before mentioned, where it will be firmly but removably held by the tap-nut C.

The construction of my invention having 55 been fully explained, its operation will be readily understood. The clipped hair will fall into the receptacle, from whence it may be emptied at certain intervals, and the use of the invention will avoid the most disagreeable features of hair-cutting, most especially the dropping of the clipped ends of the hair down the neck of the customer, where it causes great discomfort and from whence its removal is very difficult.

60 While I have illustrated and described efficient means for carrying my invention into effect, I desire it to be understood that I do not restrict myself to the exact forms and constructions shown, but hold that any slight 65 variation therefrom, such as might suggest itself to the ordinary mechanic, would clearly be included in the limit and scope of my invention.

Having thus fully described my invention, 75 what I claim as new, and desire to secure by Letters Patent of the United States, is—

1. An attachment for barbers' hair-clippers consisting of a pan or receptacle for the 80 clipped ends of the hair, adapted to be attached by the tap-nut and to extend therefrom above and in front of the handles of the clipper, substantially as described.

2. An attachment for barbers' hair-clippers consisting of a pan or receptacle for the 85 clipped ends of the hair, adapted to be attached to the clipper outside of and below the cutting-teeth, substantially as described.

GEO. M. WATSON.
